UNITED STATES PATENT OFFICE.

FELIX KOCH, OF BELLEVUE, AND ALFRED K. PEHRSON, OF PITTSBURGH, PENNSYLVANIA, ASSIGNORS TO PRESSED STEEL CAR COMPANY, OF PITTSBURGH, PENNSYLVANIA, A CORPORATION OF NEW JERSEY.

CAR CONSTRUCTION.

1,278,169.

Specification of Letters Patent. Patented Sept. 10, 1918.

Application filed February 8, 1916. Serial No. 76,898.

To all whom it may concern:

Be it known that we, FELIX KOCH, a citizen of the United States, and ALFRED K. PEHRSON, a subject of the King of Sweden, residing at No. 62 North Harrison Ave., Bellevue, and No. 1519 Davis Ave., N. S., Pittsburgh, respectively, in the county of Allegheny and State of Pennsylvania, have invented certain new and useful Improvements in Car Construction of which the following is a specification.

An object of the invention is to provide a car having side posts which extend for substantially the full height of the side walls, and which at their lower ends are bifurcated and spread apart to form diagonal braces which may be secured to the side sill or bottom chord of the side wall.

Another object of the invention is to provide a car having side posts which are slit at their lower ends, the portions resulting from such slitting being spaced apart to increase the width of the lower ends of said posts.

A further object of the invention is to provide a novel letter board and top plate construction, and a still further object of the invention is to provide a novel construction between the side posts of the car and the combined letter board and top plate.

With the above and other objects in view, the invention resides in the construction, arrangements and combinations of parts hereinafter described and claimed.

Referring now to the drawings, in which like reference characters refer to like parts, Figure 1 is a side elevational view of a portion of a car embodying the invention, portions of the side sheathing being broken away; Fig. 2 is a sectional view of the same taken on the line 2—2 of Fig. 1. Fig. 3 is an enlarged sectional view taken on the line 3—3 of Fig. 1; Fig. 4 is a side elevational view of a portion of the car showing a modification; Fig. 5 is a sectional view taken on the line 5—5 of Fig. 4; Fig. 6 is an enlarged sectional view taken on the line 6—6 of Fig. 4, and Fig. 7 is a side elevational view of a portion of the car showing a modification of the invention.

Referring now in detail to the drawings, 1 indicates the side sill or bottom chord of the side wall, 2 the combined letter board and top plate or top chord of the side wall

and 3 the side posts, which posts at their lower end portions are connected with the side sills 1, and at their upper end portions with the combined letter board and top plate 2.

Each of the posts 3 comprises a number of U or channel section having a web 4 and flanges 5, 5 projecting inwardly therefrom, such flanges being bent at an angle to form flanges 6, 6, which flanges 6, 6 strengthen the web, and for a portion of their length are adapted to form portions of a window frame. The lower end portion of the web 4 is slit in the direction of the length of the post and the resulting portions 7 and 8 are spread apart, and secured to the bottom chord 2, thus forming a wide base for the post and also forming integral diagonal braces which are substantially of Z shape in cross section.

9 indicates the lower sheathing plates of the side wall which are secured to the side posts 3 below the windows and to the side sills 2. 10 indicates a belt rail which may be secured to the sheathing plates 9 and to the posts 3. It will be understood that in some constructions this belt rail may be omitted.

The combination letter board and top plate, or top chord of the side wall, comprises a plurality of members 11, each of which is provided with a vertically disposed web 12 and top and bottom horizontally disposed flanges 13 and 14 respectively, the inner edge portion of the flange 14 being bent downwardly to form a flange 15 which strengthens the member, and may also form a portion of the window frame. To further strengthen the member 11 the web 12 is preferably provided with a corrugation 16 which may extend for substantially the full length of the member. Each of these members 11 overlaps adjacent posts and is secured to the webs 4 by rivets or other suitable means. It will be noted that each of the posts 3 is slightly offset at its upper end portion so that when the member 11 is secured to the post the outer surface 17 of the flange 14 will be in the same vertical plane as the outer surface 18 of the flange 5 of the post 3. It will further be noted that if desired the post 3 may be offset in a direction transversely of the car and that the end portions of the combined letter board and top plate may be secured to the post so that the outer surface

of such letter board will be in the same vertical plane as the outer surface of the lower portion of the post.

To further strengthen the posts 3, and to 5 form a strut therefor, members 19, preferably of channel form, may be provided which extend upwardly from and are connected with the bottom chord 1, through the 10 medium of a transverse member 31 of the underframe and the gusset plate 32, and for a portion of their length may be secured to the web 4 of the post. Above the posts these 15 members may be extended across the car to form carlines for the support of the usual roof sheets.

In Figs. 4, 5 and 6 a modified top chord 2 has been illustrated, each member 11 of which, instead of overlapping adjacent posts, is provided with end flanges 20 which 20 may be secured to the flanges 5 of the posts.

In Fig. 7 a modified construction has been 25 illustrated which comprises a bottom chord 21, a top chord 22 and a post 23 interposed between and connected to such chords. Each 30 of the posts 23 comprises a member of U or channel section having a web 24 and flanges 25, 25 projecting inwardly therefrom, which flanges at the upper end portion of the post are 35 preferably bent outwardly and are secured to the top chord 22. The lower end portion of the web 24 is slit in the direction of the length of the post and the remaining portions 26 and 27 are spread apart and are secured to the bottom chord 21, thus forming 40 a wide base for the post and also forming integral diagonal braces which are substantially of angle shape in cross section. To further strengthen the post a strut member 28 may be provided which at its upper 45 end may be secured to the portions 26 and 27 of the post and at its lower end to the bottom chord 21. 29 indicates the letter board which may comprise a plurality of members 30, which are secured throughout 50 their length to the top chord 22 and at their ends are secured to the posts 23.

The foregoing description has been limited to a passenger car, but it will be understood that if desired the invention may be 55 used in connection with freight cars.

Having thus described the invention, what we claim as new and desire to secure by Letters Patent is:

1. A post for railway passenger cars comprising a channel shaped member of uniform cross section having one of its ends slit, both of the resultant portions of said end being bent away from each other to form diagonal braces, the other end of said 60 member above said diagonal braces being substantially straight and a strut secured to said post and extending between said braces.

2. A post for railway passenger cars comprising a member of uniform channel cross 65 section having its web at one end slit, the

resultant portions of said end being bent away from each other to form diagonal braces, said portions being of less length than the remaining portion of said post, the remaining portion of said member being substantially straight to its end, and a strut for said post extending between said braces. 70

3. A post for railway passenger cars comprising a member of uniform channel cross section having lateral flanges, said member having its web at one end slit, the resultant portions of said end being bent to form diagonal braces, said portions being Z shape in cross section, the remaining portion of said member above said diagonal braces being substantially straight, and a strut secured to 75 said post and extending between said braces. 80

4. In a passenger car side wall construction comprising top and bottom chords, a belt rail between said chords, and a post secured to said chords and belt rail, said post comprising a member of uniform channel shape having its end slit below said belt rail, the resultant portions being bent to form diagonal braces, the portion of said post above said belt rail being straight and retaining its original shape. 85

5. In a passenger car side wall construction comprising top and bottom chords, a belt rail, and a post secured to said chords, said post having a straight vertical upper portion of uniform channel cross section between said belt rail and top chord, and having a pair of integral diagonal braces below 90 said belt rail. 100

6. In a passenger car side wall construction comprising top and bottom chords, a post of uniform channel cross section secured to said top and bottom chords, the lower end of said post being slit, portions of said end being bent to form diagonal braces the upper portion of said post being straight, and a belt rail secured to the straight portion of said post above the slit portion of said post. 105

7. A post for railway passenger cars having one of its ends bifurcated, the resultant portions of said end being of Z section and spaced apart and both inclined oppositely to each other, the other end of said post being substantially straight, and a strut for 110 said post located between said braces. 115

8. In a passenger car, a side wall construction comprising top and bottom chords and a post of uniform channel cross section arranged between and secured to said chords, said post having one of its ends slit, both portions of such end being bent away from each other to form diagonal braces, the opposite end of said post above said braces being substantially straight. 120

9. In a passenger car, a side wall construction comprising top and bottom chords, and a channel shaped post arranged between and secured to said chords, said post having laterally extending flanges and having 125 130

its lower end portion slit, portions of such end being bent away from each other to increase the effective width of said post, said end portions being of substantially Z section, the upper end portion of said post being substantially straight.

10. In a passenger car, a side wall construction comprising top and bottom chords, and a channel shaped post arranged between and secured to said chords, said post having its lower end portion slit, portions of such end being bent away from each other to form inclined portions of the post, and a strut extending between and connected to said post and bottom chord.

11. In a car side, the combination with a bottom chord, of a plurality of posts each having integral Z shaped diagonal braces secured to said chord, and a substantially straight vertical upper portion and a top chord comprising a plurality of members, each of said members extending only between adjacent posts and secured thereto.

12. In a car side, the combination with a bottom chord, of a plurality of posts, each having integral Z shaped diagonal braces secured to said chord, and a top chord comprising a plurality of members each of which extends only between and secured to the upper portions of adjacent posts, and each having a corrugation formed therein which extends from end to end of the member.

13. In a car side, the combination with a bottom chord, of a plurality of posts, each having integral diagonal braces secured to said chord, and a top chord comprising a plurality of corrugated members, each of which extends between and is secured to the upper portions of adjacent posts.

14. A post for railway cars comprising a member having a laterally flanged channel shaped and substantially straight upper portion and diverging Z shaped lower portions, and a strut for said post between said lower portions.

15. A post for railway cars comprising a member of channel form having lateral flanges, the lower portion of said post having its web slit, the resultant portions of the end being bent apart to form Z shaped diagonal braces, the upper portion of said post being substantially straight, and a strut secured to said post and extending between said braces.

16. A post for railway cars of channel section with laterally extending flanges having a substantially straight upper portion and having the lower end portion of its web slit centrally, both of the resultant portions of the said end being bent away from each other to form diagonal braces, and a strut secured to said upper portion and extending between said braces.

17. In a car, a side wall construction comprising top and bottom chords, webbed metal posts extending between and secured to said chords, and a belt rail secured to said posts, said posts being of uniform channel cross section and having the ends of their webs slit below said belt rail, the resultant portions of said posts so slit being bent to form diagonal braces, the portions of said posts above said belt rail being substantially straight.

18. In a car side wall construction comprising top and bottom chords, a belt rail between said chords and a post secured to said chords and belt rail, said post comprising a member of substantially uniform channel cross section having its end slit below said belt rail, portions of said end being bent apart to form diagonal braces, the portion of said post above said belt rail being substantially straight.

19. In a car wall construction comprising top and bottom chords, a belt rail, and a post connected with said chords and belt rail, said post comprising a member of uniform channel cross section throughout its length, having its end slit below said belt rail, portions of said end being bent to form diagonal wall braces, the portion of said post above said belt rail being substantially straight.

20. In a car wall construction comprising top and bottom chords, a belt rail, a post connected with said chords and belt rail, said post comprising a member, having its end slit below said belt rail portions of said end being bent to form diagonal braces, and a strut extending between and connected with said post and bottom chord.

21. In a car wall construction comprising top and bottom chords, a post connected with said chords, said post having one of its ends bifurcated, the resultant portions of said end being bent apart to form diagonal braces, and a strut connected with said post and bottom chord.

22. In a car wall construction comprising top and bottom chords, a post connected with said chords, said post comprising a member of channel form in cross section having the end of its web slit, the resultant portions of said end being spread apart, and members connected with said post and chords, the lower portions of said members forming a strut for the lower portion of said post.

23. In a car wall construction comprising top and bottom chords, a post connected with said chords, said post comprising a member of channel form in cross section having the end of its web slit, the resultant portions of said end being spread apart, and members connected with said post and chords, the lower portions of said members

forming a strut for the lower portions of said post, and the portions of said members above said top chord forming roof carlines.

24. In a car wall construction comprising top and bottom chords, a post connected with said chords, said post comprising a member of channel form in cross section having the end of its web slit, the resultant portions of said end being spread apart, and
10 channel shaped members connected with said

post and chords, the lower portions of said members forming a strut for the lower portion of said post.

In testimony whereof we affix our signatures in presence of two witnesses.

FELIX KOCH.

ALFRED K. PEHRSON.
